UNITED STATES PATENT OFFICE

CLEMENT BOOTH, OF CINCINNATI, OHIO, ASSIGNOR TO THE CINCINNATI GRINDERS,
INCORPORATED, OF CINCINNATI, OHIO, A CORPORATION OF OHIO

GRINDING MACHINERY

Application filed May 9, 1928. Serial No. 276,480.

This invention relates to improvements in grinding machinery and more particularly to that class of grinding machinery which has become known as centerless grinders.

5 In centerless grinding there are two methods generally employed, one method, known as the "thru' feed" method, wherein the work is fed axially through the grinding throat, and the other method, the one to which this 10 application relates, comprises introducing work pieces into the grinding throat laterally or axially thereof and removing them in substantially the same way. This method lends itself to the grinding of tapered and 15 other formed work and requires a formed regulating or grinding wheel or a particular arrangement of them. One of the disadvantages of grinding tapered and other formed work pieces, such as shouldered work and 20 the like, is the time lost in introducing the work pieces into the grinding throat and removing them therefrom.

An object of this invention is to provide a device wherein the tapered and other 25 formed work pieces may be automatically introduced into the grinding throat and automatically ejected or removed from the said grinding throat.

Another object of this invention is to provide 30 a device for automatically placing in and removing from the grinding throat a plurality of work pieces at one time together with mechanism for completely finishing a plurality of work pieces.

35 To accomplish these objects the invention in its broadest aspect comprises a feed member for successively introducing work pieces into the grinding throat and ejecting means for removing the said work pieces.

40 In a more specific aspect the invention comprises a hopper for holding and delivering successively individual work pieces, a reciprocating member for receiving the work pieces from the hopper and a synchronized 45 means for placing the work pieces into and displacing them from the grinding throat.

Further features of novelty in the construction and the advantages attendant thereon should be apparent by reference to the following specification taken in connection with 50

the accompanying drawings, forming a part thereof, and it will be understood that I may make any modifications in the specific details of construction or combination and arrangement of parts hereinafter disclosed within the scope of the appended claims without departing from or exceeding the spirit of the invention.

Fig. 1 is a front elevation of a centerless grinder embodying therein the features of this invention.

Fig. 2 is a fragmentary top plan view of the device shown in Fig. 1, partly shown in cross section.

Fig. 3 is a perspective view of a tapered roll adapted to be finished or ground by this invention.

Fig. 4 is a fragmentary enlarged sectional view taken on line 4—4 of Fig. 2.

Fig. 5 is a fragmentary enlarged sectional view taken on line 5—5 of Fig. 4.

Fig. 6 is a fragmentary enlarged sectional view taken on line 6—6 of Fig. 5.

Fig. 7 is an enlarged fragmentary sectional view taken on line 6—6 of Fig. 6.

Fig. 8 is an enlarged fragmentary sectional view taken on line 8—8 of Fig. 2.

Fig. 9 is a view similar to Fig. 8 showing the cam in a second position from that shown in Fig. 8.

Fig. 10 is a fragmentary enlarged sectional view taken on line 10—10 of Fig. 8.

Fig. 11 is a fragmentary enlarged sectional view taken on line 11—11 of Fig. 10.

Fig. 12 is an enlarged sectional view taken on line 12—12 of Fig. 11.

In the drawings in which similar characters of reference are employed to denote corresponding parts throughout the several views, the numeral 15 designates the bed having mounted on it, in opposition, a pair of slides 16 and 17 which rotatably support a grinding wheel 18 and a regulating wheel 19 respectively. Conventional mechanisms, such as hand wheels 20 and screws 21, may be employed for actuating the grinding and regulating wheels toward and away from one another to provide a grinding throat 22 between the said grinding and regulating wheels.

The slide 17, is provided with an end member 23 upon which blocks 24 are mounted which are connected together by a cross bar 25. Intermediate the blocks 24 there is provided 5 a housing 26 which encloses a cam plate 27. The cam plate 27 has secured to its one end a tongue 28 which extends beyond the housing 26 and is pivotally connected to a link 29. The link 29 has formed at 10 one end an elongated perforation 30 in which the pivot 31, carried by the tongue 28 is received. The link 29 is pivoted at 32 intermediate its ends and carries at its free end a roller 33 which is received in a cam groove 15 34 formed in cam drum 35 secured to the shaft 36 upon which the regulating wheel 19 is mounted. From the foregoing it will be noted that the cam plate 27 and tongue 28 are reciprocated by the link 29 through the 20 cam groove 34 formed in the cam drum 35.

The cam plate 27 has formed on it three distinct cams 37, 38 and 39 which contact rollers 40, 41 and 42 respectively. The cam plate 27 is guided by means of a slot 43 25 formed in the base 44 of the housing 26 as well as by a forked guide member 45 secured in the cover 46 of the housing 26.

The rollers 40 and 41 are rotatably mounted in the forked ends of posts 47 and 48 respectively. 30

These posts 47 and 48 are received in and reciprocated through suitable sleeves 49 which extend through perforations formed in the cam plate housing 26. The upper ends 35 of the posts 47 and 48 are bifurcated and receive the opposite ends of a work rest blade 50.

As the cam plate 27 is reciprocated through its housing the posts 47 and 48 are 40 raised and lowered through the agency of cam faces 37 and 38 and their associated rollers 40 and 41. The work rest blade 50 is also raised and lowered from the position shown in Fig. 8, where it is within the grinding throat, to the position shown in Fig. 9 where it receives the rough or unfinished work pieces from a hopper and in which position the finished work pieces are discharged 45 from the work rest blade.

The cam plate housing 26 has extending 50 from it a pair of standards 51 to which is secured a cross frame member 52 which carries a hopper 53 having passages 54, 55 and 56 therein. It will be noted that the passages 55 are curved so that they can be easily fed 55 from the front and deliver the work pieces to be ground to the proper position. The hopper 53 is provided at its base with a shaft 57 on which a star or Geneva wheel 58 is 60 formed having arms 59 extending at right angles to one another. Each of the passages 54, 55 and 56 is provided with a star or Geneva wheel at its base which passages are closed by the arms 59 to prevent a discharge 65 of the work pieces from the passages. The

arms 59 on the star or Geneva wheel 58 pass through slots or openings 66 formed in a depending lug 67 which prevent the finished work from being carried through a circle and back into the hopper and again fed into the 70 grinding throat. (See Figs. 11 and 12.) The shaft 57 is provided at its outer end with a ratchet 60 with the teeth of which a pawl 61 is in engagement. The pawl 61 is carried by an arm 62 which in turn is secured 75 to a reciprocating member 63 to which the roller 42 is secured. The reciprocating member 63 is received in and guided by a bearing member 64 secured to and carried by the cover 46 of the cam plate housing 26. The arm 62 is adapted to be elevated by the cam face 39 coming into engagement with the roller 42 and raising same. 80

It should be noted that the work rest blade has been raised to its uppermost limit (see 85 Fig. 9), before the cam face engages the roller 42 to elevate the arm 62. It will also be noted that there is a dwell in the movement of the work rest blade 50 while the arm 62 is being raised. It is during this dwell that 90 the work pieces which have been finished and are carried by the work rest blade are discharged therefrom and new pieces deposited upon the work rest. The finished work pieces are discharged from the work rest 95 blade 50 by the arms 59 into a suitable chute 65 by which they may be directed or delivered to a work receiving device.

The work rest blade 50 is also provided with recesses 68 corresponding in size and 100 position to the discharge ends of the passages 54, 55 and 56 into which the work pieces 69 are deposited. These recesses are provided with dividing lugs 70 having stop screws or 105 positioning screws 71 for terminally engaging the work pieces before they are inserted in the grinding throat. Each of the dividing lugs 70 is split, as shown at 72 in Fig. 7, and receives a transverse clamping screw 73 which may be employed to lock the set or 110 positioning screw 71 in adjusted positions.

The regulating wheel 19, as shown in the drawings, is formed to control three rolls or work pieces 69 simultaneously. It will be noted that the rolls 69 are tapered and in order to grind a taper the grinding or regulating wheel must be tapered correspondingly. In this instance the grinding wheel is formed having a plane face while the regulating wheel has three concentric flanges 74, 75 and 76 thereon, each having a face double the taper to be formed on the work piece. The flanges 74, 75 and 76 have suitable recesses or grooves 77 between them. 115

The grinding wheel 18 is approximately 125 twice the width necessary for grinding the three work pieces simultaneously. This has been provided so that the grinding wheel 18 may be reciprocated longitudinally of the work pieces to eliminate the necessity of con- 130

stantly trueing or redressing the grinding wheel. An acceptable mechanism for reciprocating the grinding wheel may be embodied herein and as the reciprocating mechanism forms no part of this invention it is deemed unnecessary to illustrate it.

The operation of the device is as follows:

Suitable mechanism is provided for rotating the grinding wheel 18 at a rapid or 10 grinding rate of speed in the direction indicated thereon by the associated arrow. Other mechanisms may be provided for rotating the regulating wheel 19 at a much slower or work rotating rate in the same direction that the grinding wheel is rotated. 15 By rotating the grinding and regulating wheels in the same direction their opposed peripheries travel in the opposite directions with respect to the work rest blade mounted 20 between the said grinding and regulating wheels. The width of the grinding throat between the wheels may be varied by manipulating the hand wheels and screws associated with the grinding and regulating wheel 25 slides.

A plurality of work pieces are placed in the passages 54, 55 and 56 through the inlet openings 78. These openings 78 are tapered so that the work pieces may be inserted in but 30 one way so that the large end of the work pieces is toward the rear of the machine. As the regulating wheel shaft is rotated and the drum thereon oscillates the link 29 about its pivot the tongue 28 is reciprocated laterally 35 of the grinding throat. This reciprocation of the tongue and its associated cam plate causes the rollers 40 and 41 to be raised by the cam faces 37 and 38 for raising the posts 47 and 48 and the work rest blade 50 secured 40 thereto. A slight dwell is caused in the movement of the work rest blade after the rollers 40 and 41 have reached the upper end of the cam faces 37 and 38. Continued movement of the cam plate 27, as seen in Fig. 9, 45 causes the cam face 39 to contact the roller 42 for raising the arm 62 and associated mechanism and rotating the shaft 57 and star or Geneva wheel secured to the said shaft. This movement or rotation of the star or 50 Geneva wheel 58 occurs, as stated above, during the dwell in the movement of the work rest blade 50 and it is during this dwell that the finished work pieces are discharged from the work rest blade and new or unfinished 55 pieces deposited thereon. The finished work pieces are deposited in the chute 65 by which they may be conveyed to a suitable container or holder.

The cam plate 27 is now shifted to the 60 right as seen in Fig. 9 whereupon the work rest blade is lowered to place the unfinished or rough pieces within the grinding throat in operative position to the grinding wheel. A slight dwell is now caused so that the work 65 pieces 69 may be properly finished. This

dwell may either be caused by the cam formed in the cam drum or by permitting the continued movement of the cam plate 27 so that the rollers 40 and 41 ride upon the flat places 80 at the base of the cam faces 37 and 38 70 and causing no movement of the work rest blade.

While this invention has been described rather minutely with regard to the embodiment shown in the accompanying drawings 75 it should be understood that numerous modifications may be made all within the scope of this invention and the claims appended hereto.

What is claimed is:

1. A centerless grinder including opposed grinding and regulating wheels forming a work receiving throat therebetween, a work rest blade disposed within the throat, means for reciprocating the work rest blade vertically through the throat, and a hopper for depositing work pieces on the work rest when the said work rest is at its upper limit of movement.

2. A centerless grinder comprising a pair 90 of opposed grinding and regulating wheels forming a grinding throat between them, a work rest within the grinding throat and adapted to be reciprocated vertically through the grinding throat, a cam plate positioned 95 beneath the work rest and adapted to be reciprocated longitudinally of the work rest, cam faces on the cam plate, depending posts carried by the work rest cooperating with the cam faces for raising and lowering the work rest, a hopper disposed above the grinding throat, and synchronized means for discharging the work pieces from the hopper on to the work rest when the said work rest is at the upper limit of travel.

3. In a centerless grinder the combination with a pair of opposed grinding and regulating wheels forming a grinding throat between them, of a work rest adapted to be vertically reciprocated through the grinding 110 throat, a hopper above the grinding throat adapted to hold and discharge work pieces on to the work rest when the said work rest is at its upper most position, and means for regulating the discharge of the work pieces 115 from the hopper adapted to be operated during the upward movement of the work rest.

4. In a centerless grinder the combination of a pair of opposed grinding and regulating wheels having a grinding throat between them, a vertically movable work rest within the grinding throat, and means for discharging work pieces on to the work rest when it is in its upper most position.

5. In a centerless grinder the combination 125 of a pair of opposed grinding and regulating wheels, a vertically movable work rest blade having posts depending therefrom, a cam plate below the work rest blade and movable longitudinally of the work rest blade having

- cam faces formed thereon cooperating with the posts carried by the work rest blade for raising and lowering said work rest blade, a hopper above the work rest blade adapted to hold and discharge work pieces on to the work rest blade, a closure means at the base of the hopper including a shaft, and means for intermittently rotating the shaft for operating the hopper closure means for discharging work pieces from the hopper.
6. In a device of the class described the combination of a pair of opposed grinding and regulating wheels forming a grinding throat between them, means for varying the grinding throat, a work rest blade within the throat adapted to be vertically reciprocated through the throat and means for placing work pieces upon the work rest blade when it is at its upper most limit of movement.
7. A centerless grinder including opposed grinding and regulating wheels forming a work receiving throat between them, a shaft associated with the regulating wheel, a work rest blade reciprocatable vertically through the grinding throat, means movable laterally of the grinding throat for vertically reciprocating the work rest blade, a tongue extending from the laterally reciprocating means, and a cam carried by the regulating wheel shaft for actuating the torque and associated laterally reciprocating means.
8. In a device of the class described the combination of a pair of opposed grinding and regulating wheels forming a grinding throat between them, a work rest blade adapted to be vertically reciprocated through the grinding throat, means disposed above the throat for successively ejecting finished work pieces from and placing unfinished work pieces on the work rest blade when it is in its upper most position.
9. In a device of the class described the combination with a pair of opposed grinding and regulating wheels forming a throat between them, of a work rest blade within the throat adapted to support a work piece in grinding position, a pair of posts secured to and depending from the blade, rollers carried by the posts at their lower ends, a reciprocating cam engaging the rollers and adapted to raise and lower the posts for raising and lowering the work rest blade for placing work pieces in and removing them from the grinding throat, and means for reciprocating the cam.
10. In a device of the class described the combination of a pair of opposed grinding and regulating wheels forming a grinding throat between them, a frame above the grinding throat, a hopper carried by the frame, a rotatable closure member having a shaft at the base of the hopper, a ratchet mechanism on the end of the shaft, a work rest blade within the grinding throat for supporting work pieces in grinding position, and means for intermittently rotating the hopper closure member for intermittently discharging work pieces from the hopper onto the work rest blade.
11. In a centerless grinder the combination of a pair of opposed grinding and regulating wheels having a grinding throat between them, a vertically reciprocable work rest blade within the grinding throat, means for moving the work rest blade, and means for discharging the work pieces from the work rest blade when it is at its uppermost limit of movement.
12. In a centerless grinder the combination of a pair of opposed grinding and regulating wheels having a throat between them, a work rest blade adapted to be vertically reciprocated through the throat, means for vertically reciprocating the work rest blade, means above the throat for holding work pieces to be finished, and means cooperating with the last mentioned means for discharging work pieces from the said last mentioned means onto the work rest blade.
13. In a centerless grinder the combination of a pair of opposed grinding and regulating wheels having a grinding throat between them, a work rest blade adapted to be vertically reciprocated through the grinding throat, a hopper having passages therein mounted above the grinding throat and adapted to hold work pieces, means at the base of the passages in the hopper for closing said passages, said means including a rotatable shaft, a fixed member having arms extending at right angles to one another and secured to the rotatable shaft for closing the passages of the hopper and for discharging finished work pieces from the work rest blade, and synchronized means for raising and lowering the work rest blade and rotating the shaft for successively displacing the finished work pieces from the work rest blade and for discharging unfinished work pieces from the hopper passages onto the work rest blade.
14. A centerless grinder including opposed grinding and regulating wheels forming a grinding throat between them, a work rest blade adapted to be vertically reciprocated through the grinding throat, a hopper above the grinding throat having passages formed therein for holding and delivering work pieces to the grinding throat, and means at the base of the hopper for preventing inadvertent discharge of the work pieces from the hopper, said means being adapted to be intermittently rotated for discharging the work pieces from the hopper.
15. In a centerless grinder the combination of a pair of opposed grinding and regulating wheels forming a work grinding throat between them, a work rest blade adapted to be vertically reciprocated through the grinding throat, a hopper above the grinding

- throat adapted to discharge work pieces on to the work rest blade when it is in its upper most position, means including a rotatable shaft having arms extending therefrom for retaining the work pieces within the hopper and preventing inadvertent discharge thereof, means for rotating the shaft and arms for discharging unfinished work pieces from the hopper on to the work rest blade and for displacing finished work pieces from the work rest blade, and means for preventing the return of the finished work pieces to the hopper.
16. In a centerless grinder the combination of a pair of opposed grinding and regulating wheels forming a grinding throat between them, a work rest blade adapted to be vertically reciprocated through the grinding throat, means for holding work pieces above the grinding throat, means associated with the holding means for regulating the discharge of the work pieces from the holding means including a rotatable shaft having arms extending therefrom, the arms being adapted to discharge the work pieces from the holding means on to the work rest blade and for displacing the finished work pieces from the work rest blade, and means for receiving the work pieces from the work rest blade and conveying them to a container.
17. In a centerless grinder the combination of opposed grinding and regulating wheels forming a grinding throat between them, a work rest blade within the grinding throat movable from a position between the proximate portions of the operative faces of said wheels to a position between the more distant portions of the operative faces of the wheels, and means for supplying a work piece to the blade when in said position between the more distant portions of the wheels.
18. In a centerless grinder the combination of opposed grinding and regulating wheels forming a grinding throat between them, a work rest blade within the grinding throat movable from a position between the proximate portions of the operative faces of said wheels to a position between the more distant portions of the operative faces of the wheels, and means for laterally discharging work pieces from the work rest blade when it is in the position between the more distant portions of the wheels.
19. In a centerless grinder the combination of a pair of opposed grinding and regulating wheels forming a grinding throat between them, a work rest blade within the throat, means for shifting the work rest blade, and means adjacent the work rest blade for receiving work pieces laterally discharged from the work rest blade.
20. In a centerless grinder the combination of a pair of opposed grinding and regulating wheels forming a grinding throat between them, a shiftable work rest blade within the
- grinding throat, and a cam member having portions thereon for shifting the work rest blade and for determining the operative association of the work piece with the blade.
21. In a centerless grinder the combination of a bed, a grinding wheel carried thereby and rotatable at a high grinding rate of speed, a regulating wheel carried by the bed in opposition to the grinding wheel and rotatable at a relatively slow work controlling rate of speed, the grinding and regulating wheels having their proximate portions spaced from one another to form a grinding throat, a work rest blade within the grinding throat and adapted to support a plurality of work pieces, and means associated with the work rest for maintaining the said work pieces in spaced relation and for holding same against axial movement relative to the active faces of the wheels while the work pieces are being simultaneously acted upon by the said wheels.
22. In a centerless grinder the combination of a bed, a pair of opposed grinding and regulating wheels carried thereby and forming a grinding throat therebetween, and a work rest blade subtending the grinding throat and having a plurality of work receiving pockets formed therein, each pocket conforming substantially to the contour of the work piece and the work rest blade presenting the plurality of work pieces simultaneously to the action of the grinding and regulating wheels.
23. In a centerless grinder the combination of a bed, a pair of opposed grinding and regulating wheels carried thereby and forming a grinding throat therebetween, and a work rest blade subtending the grinding throat and having a plurality of work receiving pockets formed therein, each pocket conforming substantially to the contour of the work piece and the work rest blade presenting the plurality of work pieces simultaneously to the action of the grinding and regulating wheels, each of said pockets in the work rest blade having an upstanding lug at one end thereof, and adjustable means extending through each lug for engagement with a terminal portion of the work within the pocket to position each work piece relative to its supporting pocket.
24. In a centerless grinder the combination of a bed, a pair of opposed grinding and regulating wheels carried thereby and forming a grinding throat therebetween, and a work rest blade subtending the grinding throat and having a plurality of work receiving pockets formed therein, each pocket conforming substantially to the contour of the work piece and the work rest blade presenting the plurality of work pieces simultaneously to the action of the grinding and regulating wheels, each of said pockets in the work rest blade having an upstanding lug

at one end thereof, adjustable means extending through each lug for engagement with a terminal portion of the work within the pocket to position each work piece relative to its supporting pocket, and means for locking the positioning means relative to the lug.

25. In a centerless grinder the combination of a bed, a grinding wheel carried thereby and rotatable at a high grinding rate of speed, a work rest blade carried by the bed adjacent the active face of the grinding wheel and adapted to support a plurality of work pieces, means associated with the work rest for maintaining the said work pieces in spaced relation and for holding same against axial movement relative to the active faces of the wheels while the work pieces are being simultaneously acted upon by the said wheels, and a regulating wheel carried by the bed in opposition to the grinding wheel rotatable at a relatively slow work rotation controlling speed and having a plurality of work engaging portions, one for each work piece carried by the work rest.

26. In a centerless grinder the combination of a bed, a pair of opposed grinding and regulating wheels carried thereby and forming a grinding throat therebetween, a work rest blade within the grinding throat having a plurality of work receiving pockets formed therein, the work rest blade being adapted to present a plurality of work pieces to the action of the grinding and regulating wheels, and a hopper mechanism carried by the bed having a plurality of work holding passages therein each in alignment with one of the pockets in the work rest blade whereby successive work pieces are fed into the work receiving pockets of the said work rest blade.

27. In a centerless grinder the combination of a bed, a pair of opposed grinding and regulating wheels carried thereby and forming a grinding throat therebetween, a work carrying and positioning member within said grinding throat, means for shifting the work carrier and positioning member from a position adjacent the proximate portions of said wheels to a position between a more distant portion thereof, and means operable during the upward movement of the work carrying and positioning member for laterally discharging the work from the member and placing additional work pieces thereon.

28. In testimony whereof I affix my signature.
CLEMENT BOOTH.
